UNITED STATES PATENT OFFICE

LOUIS MOROSINI AND JOSEPH ARICO, OF NEW YORK, N. Y., ASSIGNORS OF ONE-THIRD TO
JOHN F. MATTEO, OF NEW YORK, N. Y.

BOTTLE STOPPER

Application filed July 24, 1931. Serial No. 552,977.

This invention relates to bottle stoppers.

The essential objects of the invention are to ensure a lateral discharge at one or more points of the contents of a bottle; to retard and divide the contents of the bottle when travelling towards the point or points of lateral discharge; to prevent the surreptitious filling of a bottle after the contents thereof has been emptied; to prevent the entrance of foreign substances into the bottle; to prevent the adulteration of the contents of the bottle; to prevent tampering with the valve element of the stopper; to provide a removable closure for the lateral discharge opening or openings; and to attain these ends in a strong, durable, thoroughly efficient and comparatively inexpensive structure.

To the above ends essentially the invention consists in such parts and combinations of parts as fall within the scope of the invention as claimed.

In the drawings:

Figure 1 is a vertical sectional view of a bottle stopper, in accordance with this invention showing the adaptation thereof with respect to a bottle neck.

Figure 2 is a like view of a modified form.

Figure 3 is a section on line 3—3 Figure 1.

Figure 4 is a section on line 4—4 Figure 2.

Figure 5 is a section on line 5—5 Figure 1.

Figure 6 is a view similar to Figure 1 of still another modified form.

Figure 7 is a view similar to Figure 1 of still another modified form.

Figure 8 is a section on line 8—8 Figure 6.

Figure 9 is a section on line 9—9 Figure 8.

Figure 10 is a fragmentary view in vertical section of still another modified form.

The stopper when positioned relative to the neck 1 of a bottle is securely anchored thereto, by a suitable cementitious material arranged against the inner face of and on the edge of the neck.

Referring to Figures 1, 3 and 5 the stopper includes an annular member formed of an inner part 2, an intermediate part 3 and an outer part 4. The part 2 is of less diameter than part 2 to provide an annular shoulder 5. The part 4 is of less diameter than part 2. The part 3 is formed with an inwardly

extending annular flange 6 which merges into the inner end of part 4 and the latter opens into part 3. The outer end of part 4 is closed as at 7 and in proximity to the closed outer end of such part it is provided with a series of 55 equally spaced radially disposed openings 8 providing outlets for lateral discharge of the contents of the bottle. The lower portion of the inner face of part 3 and the upper portion of the inner face of part 2 are curved as at 9, 10 respectively. Formed integral with the inner face of the part 3 and the curved portions 9, 10 is a pair of intersecting, diametrically disposed, oppositely extending, upstanding, thin, substantially rectangular 60 partition-like-members or webs combined retarder and divider elements 11, 12 standing on their lower lengthwise edges 13 and which in connection with the inner face of part 3 provide quadrant shaped passages permanently open at their upper ends. The elements 11 and 12 intersect at the vertical medians thereof disposed at the axis of the bottle neck. The lower edges 13 of the elements 11, 12 are of arcuate contour. The upper edges 14 of said elements are squared. Mounted on the part 4 is a removable closure cap 15 for the openings 8.

The shoulder 5 seats on the edge 16 of the neck 1 and is secured therewith by the cementitious material referred to. The diameter of part 2 relative to the inner diameter of neck 1 is such as to provide tight fit and in connection with the cementitious material referred to said part 2 is securely anchored to neck 1.

The form shown in Figures 6 and 8 is the same as that shown in Figures 1, 3 and 5, with this exception that there is fixedly secured to the inner face of part 2, at the inner portion of the latter an annulus 16 having a beveled top 17 to provide a seat for a ball valve 18. The elements 11, 12 limit the outward shift of valve 18. Otherwise than that as stated the form shown by Figures 6 and 8 is identically the same as that shown by Figures 1, 3 and 5 and is anchored to the bottle neck in the same manner. The form shown in Figures 6 and 8 is of that type to prevent the refilling or

adulterating the contents of the bottle with which the stopper is used.

Referring to Figures 2 and 4 the stopper includes an annular member formed of an inner part 19 and an outer part 20 opening into each other and with the outer part closed at its outer end, as at 21. The part 19 is of less diameter than the part 20 to provide an annular shoulder 22. The lower portion of the inner face of part 20 and upper portion of the inner face of part 19 are curved, as at 23, 24 respectively. Formed integral with the inner face of part 20 and the curved portions 23, 24 is a pair of intersecting, diametrically disposed, oppositely extending, upstanding, thin, substantially rectangular partition-like-members standing on their lower longitudinal edges 27 and which in connection with the inner face of part 20 provide quadrant shaped passages permanently open at their upper ends. The elements 25, 26 intersect at the vertical medians thereof disposed at the axis of the bottle neck. The lower edges 27 of the elements 25, 26 are of arcuate contour. The upper edges 28 of said elements are squared. The part 20 in proximity to its closed outer end 21 is formed with a plurality of equally spaced radially disposed openings 29 providing outlets for lateral discharge for the contents of the bottle. Mounted on the part 20 is a removable closure cap 30 for the openings 29.

The shoulder 22 seats on the edge 16 of the neck 1 and is secured therewith by the cementitious material referred to. The diameter of part 20 with respect to the inner diameter of the neck 1 is such as to provide a tight fit and in connection with the cementitious material referred to said part 20 is securely anchored to neck 1.

The form shown in Figures 7 and 9 is the same as that shown in Figures 2 and 4, with this exception that there is fixedly secured to the inner face of part 19, at the inner portion of the latter an annulus 31 having a beveled upper top 32 to provide a seat for a ball valve 34. The elements 25, 26 limit the outward shift of valve 34. Otherwise than that as stated, the form shown by Figures 7 and 9 is identically the same as that shown by Figures 2 and 4 and is anchored to the bottle neck in the same manner. The form shown in Figures 7 and 9 is of that type to prevent the refilling or adulterating the contents of the bottle with which the stopper is used.

The form shown by Figure 10 will be the same as that illustrated by Figure 6 or by Figure 7, with this exception that the annulus 35 for the ball valve 36, does not have its top beveled, but includes a pair of diametrically disposed, oppositely extending, intersecting webs 37 cut out in the top edges thereof to form a valve seat 38.

What we claim is:—

1. A bottle stopper including an annular member having a closed outer end, an open inner end for extension into the bottle neck and a peripheral shoulder for overlapping the mouth edge of the bottle neck, said member having radial openings in proximity to its closed end to provide lateral discharge points, and a pair of diametrically disposed, oppositely extending, upstanding, thin, substantially rectangular partition-like-members standing on their lower lengthwise edges and providing combined retarder and divider elements integral at their ends with the inner face of said member intermediate the ends of the latter, intersecting each other at the axis of the bottle neck and forming in connection with said inner face quadrant shaped passages permanently open at their outer ends. 70 75 80

2. A bottle stopper including an annular member having a closed outer end, an open inner end for extension into the bottle neck and a peripheral shoulder, said member having radial openings in proximity to its closed end to provide lateral discharge points, a pair of diametrically disposed, oppositely extending, upstanding, thin, substantially rectangular partition-like-members standing on their lower lengthwise edges and providing combined retarder and divider elements integral at their ends with the inner face of said member intermediate the ends of the latter, intersecting each other at the axis of the bottle neck and forming in connection with said inner face quadrant shaped passages permanently open at their outer ends, 85 90 95 100 105 110 115 120 125 130

3. A bottle stopper including an annular member having a closed outer end, an open inner end for extension into the bottle neck and a peripheral shoulder for overlapping the mouth edge of the bottle neck, said member having radial openings in proximity to its closed end to provide lateral discharge points, a pair of diametrically disposed, oppositely extending, upstanding, thin, substantially rectangular partition-like-members standing on their lower lengthwise edges and providing combined retarder and divider elements integral at their ends with the inner face of said member intermediate the ends of the latter, intersecting each other at the axis of the bottle neck and forming in connection with said inner face quadrant shaped passages permanently open at their outer ends, and a removable closure for said discharge openings seating on said closed outer end. 110 115 120 125 130

In testimony whereof, we affix our signatures hereto.

LOUIS MOROSINI.
JOSEPH ARICO.
